United States Patent Office.

E. B. HAMLIN, OF ST. LOUIS, MISSOURI.

Letters Patent No. 83,849, dated November 10, 1868.

IMPROVEMENT IN PAINT-CANS.

The Schedule referred to in these Letters Patent and making part of the same.

To all whom it may concern:

Be it known that I, E. B. HAMLIN, of St. Louis, in the county of St. Louis, and State of Missouri, have made certain new and useful Improvements in Cans; and I do hereby declare that the following is a full and clear description thereof, reference being had to the accompanying drawings, and to the letters of reference marked thereon.

The object of this invention is to make an improved metal can for containing such articles as leads, oils, paints, &c., &c.

The invention relates, first, to an improved reinforced band around the top edge of the can, for stiffening the same, so as to more securely hold the cover in place; secondly, to an adjustable bail for the said can; and thirdly, to a locking-attachment for holding the cover in place in the can during its transportation.

To enable those skilled in the art to make and use my improved can, I will proceed to describe its construction and operation.

Figure 1 is a side elevation of the improved can.

Figure 2 is a sectional elevation of the same.

Figure 3 is a sectional elevation of the reinforced ring or band for strengthening the top edge of the can.

Figure 4 is a plan of the reinforcing-band.

The body of the can A is made in the usual manner, and the bottom plate A' is securely soldered to it. The top edge of the can is strengthened by a reinforcing-band, B, of sheet-metal, and formed by pressing or stamping. This band has a lip, b, at its top edge, as is best shown in fig. 3. This lip is curved over outwardly, so as to envelop the top edge of the can when the band is placed in position thereon. The lip may then be hammered down upon the can, and the two parts are securely united together.

The inside of the band B may have a flange, b', for receiving and sustaining the can-cover, but this flange may be dispensed with when using covers C, similar to those shown in the drawings.

The cover C has a curved lip, c, at the top edge of its side rim, so arranged as to overlap and envelop the

top edge of the can. This lip will, of course, hold the cover in its proper position without the use of the flange b'.

The can has a bail, D, which passes through holes in the ear-pins d, the said ear-pins being arranged to turn in their socket-pieces d', which are secured to the sides of the can.

As these cans have to be packed in cases in large quantities, it becomes necessary to arrange the handle or bail-pieces D, so they may be as much out of the way as possible when thus packed in boxes. To accomplish this result, the ear-pins d have holes entirely through them for the handle D, and the said handles have their ends upset, or enlarged, so as to prevent their being withdrawn through the pins d'. This construction permits the handles to be drawn out, as in the full lines of fig. 1, when the can is to be used as a pail, or closed up against the side of the can, as in the dotted lines of the same figure, the latter being the position necessary for packing the cans in boxes.

The cover C being fitted tightly into the top of the can, it only requires two locking-pieces, E, to securely fasten it therein. These locking-pieces are simply wire fastenings, having their lower ends secured in the ear-pieces d', and their upper ends arranged to bend over the top of the cover-piece after it is in position in the can, thereby securely holding it in place.

Having described my invention,

What I claim, is—

1. The reinforcing-band B, when constructed with a lip, b, at its top edge, and attached to the can A, in the manner and for the purpose herein described and set forth.

2. The locking-pieces E, when constructed and employed as and for the purpose herein shown and described.

E. B. HAMLIN.
